UNITED STATES PATENT OFFICE.

SAMUEL MAY, OF TORONTO, CANADA.

BILLIARD-CUSHION.

SPECIFICATION forming part of Letters Patent No. 687,641, dated November 26, 1901.

Application filed May 27, 1901. Serial No. 62,135. (No model.)

To all whom it may concern:

Be it known that I, SAMUEL MAY, a subject of the King of Great Britain, and a resident of Toronto, in the Province of Ontario and 5 Dominion of Canada, have invented a new and Improved Billiard-Cushion, of which the following is a full, clear, and exact description.

The object of the invention is to provide a 10 new and improved billiard-cushion arranged to insure proper repelling of the balls by the use of two or more graduated springs, so that the force of the ball when the latter presses the cushion immediately reaches the steel 15 springs and through them receives repelling power from near the center of the rubber cushion to prevent loss of speed in the ball and also to prevent the latter from hopping or jumping from the table and at the same 20 time insure deflection of the ball at an angle equal to the angle of incidence.

The invention consists of novel features and parts and combinations of the same, as will be fully described hereinafter and then 25 pointed out in the claims.

A practical embodiment of the invention is represented in the accompanying drawings, forming a part of this specification, in which similar characters of reference indicate corresponding parts in both the views.

Figure 1 is a cross-section of the improvement as applied, and Fig. 2 is a perspective view of the rubber-lined cloth with part of the cloth shown detached from the rubber.

35 The rail A of the billiard-cushion is formed with the usual seat for an elastic rubber cushion B, in which are embedded throughout its length the resilient ribbons or bands C C', preferably made in the form of steel bands 40 placed one behind the other and arranged parallel to the inner or playing side of the cushion. The ribbons are graduated in thickness and width, and the ribbon C, close to the inner side of the billiard-cushion, is made 45 widest, the succeeding ribbons diminishing in width, as indicated in Fig. 1. The upper edge of the ribbon C reaches close to the top of the rubber cushion B, while the upper portion of the next adjacent ribbon C' is below 50 the upper part of the ribbon C and lies about the middle of the cushion B, so that when the ball strikes the rubber cushion and flexes the

latter outward then the ribbon C is bent in a like direction and presses against the next ribbon C', so that the main repelling power 55 of the ball comes from the ribbon C'—that is, from near the middle portion of the rubber cushion B—and hence is more effective to deflect the ball at an angle equal to the angle of incidence, thereby rendering the cushion extremely sensitive and preventing hopping or jumping of the ball from the table.

There is a great difference in the size and weight of the balls used on billiard-tables. For instance, on a six-by-twelve table balls as 65 small as two and one-sixteenth inches diameter and four and one-half ounces weight are used. On pool-tables the balls are generally two and one-fourth inches in diameter and six ounces in weight, while on carom-tables the 70 balls range from two and three-eighths inches to two and one-half inches in diameter and seven and one-fourth to eight and one-half ounces weight. From this it is evident that a cushion made strong enough to carry balls 75 of eight and one-half ounces weight would be altogether too stiff for a ball of four and one-half ounces weight, and hence it is very desirable to permit of constructing a cushion graduated as to its elasticity or repelling 80 power according to the intended use, and this result is readily obtained by the use of the graduated springs above described.

In order to render the repelling power of the cushion still more effective, I provide the 85 rail-cloth D with an inner pure-rubber lining D', so that the lining clings or adheres more firmly to the rubber of the cushion B, and thereby causes the cloth to coat more positively with the resiliency of the rubber cushion 90 B when struck by the ball to prevent slipping of the cloth on the cushion, thereby diminishing its speed, as is so frequently the case with the ordinary cloth now used on the rails. By the arrangement described the propelling 95 power of the cushion is greatly increased and the loss of speed through this slippage is eliminated. By having the rubber lining on the cloth D it is evident that dust, chalk, and other fine particles are prevented from settling between the rail and its cloth covering, so that the efficiency of the cushion is not impaired on that account. The rubber lining 100 renders the cloth more durable, and as the

firmly-adhering cloth acts in unison with the cushion-repelling spring-ribbons it is evident that an exceedingly-active billiard-cushion is produced.

5 I am aware that it is not new to use a metallic ribbon embedded in the rubber cushion, as such arrangement is shown in my Patent No. 283,129, dated August 14, 1883, and I am also aware that it is not new to use a plurality of springs to give a cushioning effect, as indicated in the patent to Joseph Rivoire, No. 317,017, granted on May 5, 1885.

Having thus fully described my invention, I claim as new and desire to secure by Letters 15 Patent—

1. A billiard-cushion, comprising a rail, a rubber cushion set therein, a plurality of elastic graduated ribbons embedded in the rubber cushion, and a cover of cloth having a 20 rubber lining adhering to the face of said rubber cushion, as set forth.

2. A billiard-cushion, comprising a spring, a rubber body inclosing said spring, and a detachable covering of duplex texture, composed of a sheet of rubber and a sheet of cloth, vulcanized together, said covering be- 25

ing separate from said massive rubber body but held in immediate contact therewith.

3. A billiard-cushion, comprising a rubber body covered with a separate fabric, said fabric consisting of a thin sheet of rubber and a thin sheet of cloth vulcanized together and placed upon said rubber body so as to present an internal face of sheet-rubber detached from said rubber body, but held in 35 immediate contact with the external face of the same.

4. A billiard-cushion, comprising a spring, a resilient rubber body inclosing said spring and a separate covering of duplex texture, 40 the same being made of a thin sheet of cloth and a thin sheet of rubber vulcanized together, said separate covering being entirely distinct from said rubber body and placed upon the same with the cloth side outward. 45

In testimony whereof I have signed my name to this specification in the presence of two subscribing witnesses.

SAML. MAY.
